UNITED STATES PATENT OFFICE.

ADOLPH M. BARRON, OF KANSAS CITY, MISSOURI.

THERMOSTAT.

SPECIFICATION forming part of Letters Patent No. 446,846, dated February 24, 1891.

Application filed September 19, 1890. Serial No. 365,530. (No model.)

To all whom it may concern:

Be it known that I, ADOLPH M. BARRON, of Kansas City, Jackson county, Missouri, have invented certain new and useful Improvements in Thermostats, of which the following is a full, clear, and exact description, reference being had to the accompanying drawings, forming a part hereof.

My invention relates to improvements in thermostats for fire-alarm purposes; and it consists in the peculiar combination and arrangement of devices, as will be hereinafter described, and pointed out particularly in the claims.

My object is to provide a simple, cheap, and more effective device of this character, using less wire for the main circuit than is now in use.

Referring to the drawings which illustrate the invention, Figure 1 is a view showing my improved thermostat as arranged for use. Fig. 2 is a top plan view of the thermostat. Fig. 3 is a vertical sectional view of the same, taken through the binding-posts. Fig. 4 is a vertical sectional view taken on a line $x-x$ of Fig. 2. Fig. 5 is a bottom plan view of the thermostat.

A represents a thermostat, consisting of the porcelain base-block B, provided with a central vertical opening therethrough, in which is secured the casing C, which has a vertical screw-threaded opening D therethrough, in which is adapted to be secured the upper screw contact-point E.

A circular recess, concave when looking toward the bottom, is formed in the disk B, in which is secured the concave metallic disk F by bolts G, which disk is adapted to expand when subjected to an excessive heat.

A metal cross-bar H is secured to the under surface of the annular flange I, formed by recessing the base-block B at F' by the securing-screws J J', passing through the base-block B, and being in vertical alignment with the binding-posts K K', secured in the recesses in the upper surface of base-block B, engage the screw-threaded vertical passages L and L' therein.

Secured in the upper end of passages L and L' in posts K and K' are the screws M. Conducting-strap N is connected at one end to the casting C by screw O, and the opposite

end is bent down and under the binding-posts K, said end being provided with a perforation, through which the screw J passes. 55

The bolts G, which secure the expansion-disk in place in the recessed surface of the base-block B, extend through vertical passages in said base-block B and are engaged by nuts P, resting in recesses in the upper 60 surface of the said disk.

A conducting-strap Q is bent down at either end under the binding-post K' and one of the nuts P, the said ends being provided with perforations, through which pass the screw J' 65 of binding-post K' and screw-bolt G of disk F, and thus connecting binding-post K' and expansion-disk F, as will be readily understood.

An insulator R, of suitable material, prevents contact between screws J' and connecting-bar H, thus breaking the circuit, as will be readily understood, when the disk F is not in contact with the lower contact-point S, secured in vertical screw-threaded passages T of cross-bar H, or with the point E, the former 75 being its normal condition.

The operation of the invention is as follows: The thermostat is suspended from the ceiling of the building in a suitable manner by the connection of the wire with each binding-post. 80 Situated in convenient position in the building is the house-box, shunt-coil, and open-current battery. In case of fire or other excessive heat the disk F expands, leaving the lower contact-point S. This causes the current 85

passing from the main battery 1, through main relay 2, to and from house-box 3 to binding-post K, and the circuit being broken passes through the wire 4 to shunt-coil 5, energizing the same and attracting the armature 6, which 90 completes the open circuit. The trip-coils 7, being thus energized through wire 8, attracts the armature 9, raising the trip-arm 10 and allowing the revolution of the circuit-wheel 11, provided with suitable projections on its 95 periphery, signifying the location of the box, the current returning to the main battery by way of the house-box and main relay, and thus notifying the central office, as will be readily understood. Immediately the disk 100 expands sufficiently to come into contact with upper contact-point E the circuit is completed, the current passing from the binding-post K, through conducting-strip N to casting

C, through upper point E to expansion-disk F, thence through bolt G, conducting-strap Q, binding-post K', and main wire to main battery. As soon as the current is completed 5 in the manner described the current ceases to pass through wire 4 and energize the shunt-coils 5, and the armature 6 therefore resumes its normal position and the open circuit is broken. When the armature 6 resumes 10 its normal position, the armature 9 and trip-arm 10, descending, prevent the revolution of the circuit-wheel, as will be readily understood.

Having thus fully described my invention, 15 what I claim as new, and desire to secure by Letters Patent, is—

1. In a thermostatic circuit-controlling device, the combination of an insulating-block having a recessed under surface, a disk 20 sensitive to variations of temperature contained in the said recess, two binding-screws on the said base, a cross-bar below the said disk, having a contact-point thereon normally in contact with the said disk and connected 25 with one of the said binding-posts, and a metallic casting in the said block, having a contact-point projecting from its base within the said recess and connected with the said bind-

ing-screw, the said disk being connected with the opposite binding-post, as described. 30

2. In a thermostatic circuit-controlling device, the combination of an insulating base-block having a recessed under surface, a disk 35 sensitive to variations in temperature within the said recess, a bolt passing through the said disk and the base-block, a binding-post upon the said block, and a strip connecting the said bolt and binding-post, a cross-bar 40 spanning the said recess below the said disk and having a contact-point in its upper surface normally in contact therewith, a screw passing through one end of the said bar and insulated therefrom and extending into the said binding-post, a casting within the said block, having a contact-post projecting from 45 its bottom over the said disk, a screw passing through the other end of the said bar and through the block, and a binding-point mounted thereon and connected with the said casting, as described. 50

In testimony whereof I affix my signature in presence of two witnesses.

ADOLPH M. BARRON.

Witnesses:

H. C. JOHNSON,
L. J. HIGDON.
